(57) **CLAIM**

The ornamental design for an optical coherence tomography system, as shown and described.

DESCRIPTION

FIG. 1 is a front perspective view of an optical coherence tomography system;

FIG. 2 is a front elevational view of the optical coherence tomography system;

FIG. 3 is a rear elevational view of the optical coherence tomography system;

FIG. 4 is a right elevational view of the optical coherence tomography system;

FIG. 5 is a left elevational view of the optical coherence tomography system;

FIG. 6 is a top view of the optical coherence tomography system; and,

FIG. 7 is a bottom view of the optical coherence tomography system.

The broken lines in FIGS. 1-7 are for illustrative purposes only and form no part of the claimed design.
